UNITED STATES PATENT OFFICE.

RUFUS BOLDRY, OF CHATSWORTH, ILLINOIS, ASSIGNOR OF ONE-HALF TO JOHN CARNEY, OF CHATSWORTH, ILLINOIS.

MARKER FOR CORN-PLANTERS.

992,401.

Specification of Letters Patent. Patented May 16, 1911.

Application filed November 18, 1910. Serial No. 593,102.

To all whom it may concern:

Be it known that I, RUFUS BOLDRY, a citizen of the United States, residing at Chatsworth, in the county of Livingston and State 5 of Illinois, have invented a new and useful Marker for Corn-Planters, of which the following is a specification.

The invention relates to improvements in devices for raising, lowering and reversing 10 land markers.

The object of the present invention is to improve the construction of devices for raising, lowering and reversing land markers, and to provide a simple and comparatively 15 inexpensive construction of great strength and durability, adapted to be readily applied to an ordinary planter, and capable of convenient operation by the driver to raise and lower the marker to clear a stump or 20 other obstruction, and to reverse the marker from one side of the machine to the other when turning at the end of a row.

With these and other objects in view, the invention consists in the construction and 25 novel combination of parts hereinafter fully described, illustrated in the accompanying drawings, and pointed out in the claims hereto appended; it being understood that various changes in the form, proportion, size 30 and minor details of construction, within the scope of the claims, may be resorted to without departing from the spirit or sacrificing any of the advantages of the invention.

In the drawings:—Figure 1 is a rear elevation of a marker operating device, constructed in accordance with this invention and shown applied to a planter. Fig. 2 is a perspective view of the device and a portion of the frame of the planter. Fig. 3 is a plan 40 view of the same. Fig. 4 is a detail sectional view, taken substantially on the line 4—4 of Fig. 3, the marker bar being in an elevated position. Fig. 5 is a detail sectional view 45 on the line 5—5 of Fig. 4. Fig. 6 is a detail sectional view on the line 6—6 of Fig. 1.

Like numerals of reference designate corresponding parts in all the figures of the drawings.

In the embodiment of the invention illustrated in the accompanying drawings, the marker operating device comprises in its construction a horizontally disposed bearing bracket 1, disposed transversely of the rear end of a planter frame 2, and preferably ar-

ranged in the same horizontal plane as the 55 frame, as clearly illustrated in Fig. 2 of the drawings. The bearing bracket is preferably composed of two transverse bars or members 3 and 4, having flat intermediate portions fitted against each other and secured together by rivets 5, or other suitable fastening means, but the bearing bracket may consist of a single casting if desired. The inner portions 6 and 7 of the bars or members of the bracket diverge from the intermediate portions and are spaced apart and provided with aligned bearing openings 8 and 9, located centrally of the planter or in the plane of the median line thereof. The inner terminal portion 10 of the bar or member 4 is angularly bent to form an approximately L-shaped arm, which is fitted against the inner terminal of the other bar or member 3. The inner portion 6 of the bar or member 3 is bowed rearwardly at 11 to offset its bearing opening from the rear transverse end bar or portion of the frame of the planter, and it is secured to the rear end bar of the planter frame by clips 12 and 13, which embrace the rear end bar of the 80 planter frame. The clip 12 pierces the inner portion 6 of the bar or member 3 and is equipped with nuts, which engage the inner face thereof. The sides of the other clip 13 pierce the inner terminals of both of the 85 bars or members, and its nuts engage the outer face of the bars or members 4. The outer terminals 14 and 15 of the bars or members 3 and 4 project beyond one side of the frame and extend laterally therefrom 90 and are off-set from each other and spaced apart to provide an intervening space or recess 16.

The aligned bearing openings 8 and 9 receive a crank pivot 17, secured in the bearings of the spaced inner portions of the bars or members of the bracket 1 by means of a key 18, piercing the pivot and arranged at the inner face of the inner portion 7 of the bar or member 4, as clearly illustrated in 100 Fig. 4 of the drawings, but the pivot may be secured to the bearing bracket in any other desired manner. The crank pivot is provided at its rear end with an arm 19, having an outwardly projecting integral terminal lug 20, secured between spaced ears or flanges 21 of a marker bar 22 by a bolt 23, or other suitable fastening device. The bolt

forms a pivotal pintle and with the lug and the ears provide a hinged connection between the marker bar and the pivot to permit the marker bar to swing backward with-
5 out straining the pivot should it come in contact with an obstruction. The pivot 17 extends longitudinally of the planter, and the marker bar swings transversely of the planter from one side to the other thereof in
10 the usual manner.

The ears or flanges 21 are formed integral with a bar or plate 24, extending along the front face of the inner end of the marker bar and secured to the same by a plurality
15 of bolts 25, or other suitable fastening devices, which pierce the plate or bar 24 and the marker bar. The plate or bar 24 is provided at one side with a laterally projecting approximately V-shaped extension 26,
20 formed integral with the plate or bar and composed of outwardly converging angularly related upper and lower sides. The lower side of the V-shaped extension is provided with a plurality of perforations 27
25 for the reception of a bolt 28, or other suitable fastening device, which adjustably connects the inner end of a link 29 with the marker bar. The link 29 is provided at its ends with a plurality of perforations 30, and
30 the bolt 28 is adapted to be arranged in any of the perforations to adjust the link and the marker bar. The link consists of a round rod, and its inner end, which is provided with the perforations 30 is flattened as
35 shown and is adapted to fit against the front face of the V-shaped extension 26.

The outer portion of the link 29 extends through a slot 31 of a flange 32 of an operating lever 33, fulcrumed at an intermediate
40 point in the recess 16 and extending below the bracket 1. The flange 32 is formed integral with an attaching plate or flange 34, which is riveted or otherwise secured to the rear face of the operating lever 33. The
45 flange 32 projects from the rear face of the lever 33 and the slot 31 extends longitudinally thereof. The outer end of the link is provided with a stop 35, adapted to engage the projecting flange 32 to prevent the
50 link from being withdrawn from the slot 31. The outer stop 35 may consist of a bolt, key, or other suitable fastening device, and a washer is preferably arranged at the inner side of the same, as shown. The link
55 is also equipped with an inner stop 36, located at an intermediate point between the ends of the link and forming a bearing for a coiled spring 37, interposed between the stop 36 and the flange 32. The inner stop
60 is of the same construction as the outer stop, and the coiled spring is adapted to create a pressure on the marker bar for forcing a marker 38 into the ground. The operating lever 33 is pivoted in the slot or
65 recess 16 of the bearing frame by a bolt 39,

or other suitable fastening device, and it is adapted to be oscillated to raise and lower the marker bar and to swing the same from one side of the machine to the other. When the marker bar is lowered and the lever is 70 in the position illustrated in Fig. 1 of the drawings, both the spring and the outer stop are spaced from the projecting flange 32, and the marker is free to move upwardly and downwardly to conform to the configuration 75 of the ground and to drop into depressions or low places thereof. By moving the lever inwardly from such position, it is carried into contact with the coiled spring 37 and is adapted to place the same under tension 80 to cause the spring to press the marker into the soil. The lever is equipped with a spring actuated dog or detent 40, arranged to engage a toothed segment 41 having supporting arms 42, which are secured to the 85 outer end 14 of the bar or member 3. The dog or detent is controlled by a latch lever mounted on the operating lever and located adjacent to the handle of the outer portion thereof to enable the latch lever and the operating lever to be simultaneously grasped.
90

The lower depending arm or portion 43 of the operating lever is loosely connected by a link 44, or a plurality of links with the outer end of a coiled spring 45, which is 95 provided at its inner end with an eye 46, which is linked into an eye 47 of a rod 48, located beneath and extending longitudinally of the bearing bracket. The inner terminal portion 49 of the rod 48 is threaded 100 and extends through a depending perforated lug 50 of the angularly bent inner end 10 of the outer bar or member 4, and the said threaded inner portion 49 is equipped with a nut 51 for adjusting the spring.
105

The downward swinging of the marker bar from the elevated position illustrated in Fig. 2 to the ground at either side of the planter, places the spring 45 under tension, producing a slow downward movement and assisting the operator in both lifting and controlling the marker bar. When the operating lever is locked in the position illustrated in Fig. 1 of the drawings, the tension of the coiled spring 45 does not affect the 110 free up and down movement of the marker bar, but as soon as the operating lever is released and the spring permitted to act, it will assist the upward movement of the marker. The movement of the operating lever to the right or outwardly from the position shown in Fig. 1, raises the marker until the marker bar assumes practically a perpendicular position, the coiled spring 45 assisting such upward movement. The momentum of the marker bar will carry it beyond the center, and as it descends at the opposite side of the planter the lever moves backwardly or inwardly, and the spring 45 is placed under tension. The locking of 115
120
125
130

the lever not only relieves the marker bar of the tension of the spring 45, but enables pressure to be placed on the marker through the spring 37.

5 Having thus fully described my invention, what I claim as new and desire to secure by Letters Patent, is:—

1. A device of the class described including a pivotally mounted marker bar arranged to swing transversely of a planter from one side to the other, an operating lever also arranged to swing transversely of the planter and connected with the marker bar for swinging the same, and a transversely disposed spring connected directly to the lever and arranged to be placed under tension by the downward movement of the marker bar.

2. A device of the class described including a pivotally mounted marker bar arranged to swing transversely, an operating lever spaced from the marker bar and provided at an intermediate point with a pivot, means located at one side of the pivot of the lever for connecting the same with the marker bar, and a coiled spring connected with the marker bar at the opposite side of the pivotal point and arranged to be placed under tension as the marker bar swings downward.

3. A device of the class described including a pivotally mounted marker bar arranged to swing transversely of a planter from one side to the other of the same, an upright lever pivoted at an intermediate point and spaced from the pivot of the marker bar, means located above the pivot of the lever for connecting the latter with the marker bar, and a spring connected to the lever below the pivotal point thereof and arranged to be placed under tension by the downward movement of the marker bar.

4. A device of the class described including a pivotally mounted marker bar arranged to swing transversely of a planter from one side to the other of the same, an upright lever pivoted at an intermediate point and spaced from the pivot of the marker bar, means located above the pivot of the lever for connecting the latter with the marker bar, a spring connected at one end with the lever below the pivotal point thereof and arranged to be placed under tension by the downward movement of the marker bar, and a fixed adjusting device connected with the other end of the spring.

5. A device of the class described including a pivotally mounted marker bar arranged to swing transversely of a planter, an upright lever, a link connected with the marker bar and having a limited movement on the lever, a spring connected with the lever and arranged to be placed under tension by the downward movement of the marker bar, and means for locking the lever

to relieve the marker bar of the tension of the spring to permit a free up and down movement of the marker bar.

6. A device of the class described including a pivotally mounted marker bar arranged to swing transversely of a planter, an upright lever, a link connected with the marker bar and having a limited movement on the lever, and a spring mounted on the link and arranged to be placed under tension by the lever for forcing the marker bar downwardly.

7. A device of the class described including a pivotally mounted marker bar arranged to swing transversely of a planter, an upright lever, a link connected with the marker bar and having a limited movement on the lever, a spring mounted on the link and arranged to be placed under tension by the lever for forcing the marker bar downwardly, another spring connected with the lever and arranged to be placed under tension by the downward movement of the marker bar, and means for locking the lever to relieve the marker bar of the tension of the last-mentioned spring to permit either a free movement of the marker bar or the action of the first-mentioned spring.

8. A device of the class described including a pivotally mounted marker bar provided with a laterally projecting tapering extension having a plurality of perforations, a pivoted lever, a link connected with the lever, a fastening device arranged in one of the perforations of the said extension and adjustably connecting the link to the same, and a spring also connected to the lever and arranged to be placed under tension by the downward movement of the marker bar.

9. A device of the class described including a pivotally mounted marker bar arranged to swing transversely, a pivoted lever provided with a projecting flange having a slot, a link connected with the lever and extending through the slot and provided with inner and outer stops located at opposite sides of the lever, a coiled spring disposed on the lever and interposed between the inner stop and the lever, and locking means for the lever to permit a free movement of the marker bar and also for enabling the spring to be placed under tension to press the marker bar downwardly.

10. A device of the class described including a pivot, a marker bar, a plate secured to the marker bar and connected with the pivot and having a laterally projecting substantially V-shaped extension, a pivoted lever, a link connecting the pivoted lever with the V-shaped extension, and a spring connected with the lever and arranged to be placed under tension by the downward movement of the marker bar.

11. A device of the class described including a transversely disposed bearing bracket

provided at its inner portion with spaced front and rear bearings and having a recess at its outer portion, a pivot mounted in the said bearings, a marker bar carried by the 5 pivot and arranged to swing transversely of a planter, a lever pivoted in the recess and connected with the marker bar, a toothed segment mounted on the bearing bracket at one side of the recess, and means carried by 10 the lever for engaging the toothed segment.

12. A device of the class described including a transverse bearing bracket provided at its inner portion with spaced bearings and having a depending lug, a pivot mounted in 15 the said bearings, a marker bar carried by the pivot, a lever mounted on the bearing bracket at the outer portion thereof and extending below the same, means for connecting the upper portion of the lever with the marker bar, a spring connected with the 20 lower portion of the lever, and a threaded rod connected with the spring and extending through the said lug and provided with a nut located at the lug for adjusting the rod 25 to vary the tension of the spring.

13. A device of the class described including a transverse bearing bracket composed of two bars or members having intermediate portions secured together, the outer portions of the bars or members being spaced apart 30 and the inner portions being also spaced apart and having bearings, the inner terminals of the bars or members being fitted against each other and secured together, a pivot mounted in the said bearings, a marker 35 bar carried by the pivot, a lever pivoted between the outer ends of the bars or members, means for connecting the marker bar with the spaced portion of the lever, and a spring located beneath the bearing bracket and connected with the lower portion of the lever and with the said bracket.

In testimony, that I claim the foregoing as my own, I have hereto affixed my signature in the presence of two witnesses.
